(57) **CLAIM**

We claim the ornamental design for a bicycle carrier, as shown and described.

DESCRIPTION

FIG. 1 is a perspective view of a bicycle carrier constructed in accordance with the present invention.

FIG. 2 is a left side elevation view thereof.

FIG. 3 is a right side elevation view thereof.

FIG. 4 is a top plan view thereof.

FIG. 5 is a bottom plan view thereof.

FIG. 6 is a front elevation view thereof; and,

FIG. 7 is a rear elevation view thereof.

The dashed line(s) shown in the drawings are for illustrative purposes only and form no part of the claimed design.

The stippling and shading lines shown in the drawing(s) represent the approximate three-dimensional contour of the design, and are not intended to indicate surface decoration. Portions of the bicycle carrier that are not shown in the drawing(s) form no part of the claimed design.
